FOOD CONTAINER

Robert Daenen, Beukenlaan, Belgium, assignor to Dart Industries, Inc., Los Angeles, Calif., a corporation of Delaware

Filed Feb. 25, 1970, Ser. No. 21,625

Term of patent 14 years

Int. Cl. D7—99

U.S. Cl. D44—1

FIG. 1

FIG. 2

FIG. 3

FIG. 4

FIG. 5

FIG. 6

FIG. 1 is an exploded perspective view of a food container showing my new design;

FIG. 2 is an exploded perspective view with the tray member in inverted position;

FIG. 3 is a perspective view of FIG. 1, in closed condition;

FIG. 4 is a fragmentary sectional view on line 4—4 of FIG. 1, and with the cover in closed condition;

FIG. 5 is a perspective view of FIG. 2, in closed condition; and

FIG. 6 is a bottom plan view of the cover member.

I claim:

The ornamental design for a food container, substantially as shown.
